UNITED STATES PATENT OFFICE.

HOOTON J. COON, OF EVANSTON, ILLINOIS.

SAFETY LATCH FOR BANK VAULTS.

Application filed December 19, 1927. Serial No. 249,979.

The latch of the present invention is designed as an improvement on the latch set forth in my application, Serial No. 203,046, filed July 2, 1927. The latch of the present invention is designed to prevent the complete closing of a bank vault door by robbers, so that bank officials who may be confined within the vault will not be in danger of suffocation. The latch is so arranged that in an emergency, when the door is swung to, it will be latched and held ajar, so that thereafter the intruders can neither open or close the door.

The improvements which particularly form the subject matter of the present invention refer to the means provided for automatically setting or conditioning the latch against an emergency when the door is opened by the bank officials in the morning. This feature is of importance by reason of the fact that without it there is danger through inattention on the part of bank employees that the latch may remain in the disabled condition in which it is adjusted when the vault door is locked for the night.

In the drawings:

Figure 1 is a face view of a vault door and casing looking from the inside, and with the latch thrown;

Fig. 2 is an enlarged sectional detail of the latch in position on the door;

Fig. 3 is a perspective view of the latch;

Fig. 4 is a fragmentary perspective view of the door and casing illustrating the means for setting the latch by the opening of the door; and

Fig. 5 is a detail in section showing a modification in which the latch member is mounted upon the casing rather than upon the door.

The device is applied to a vault door 10 of the usual character having near its margin on the inner side a bolt rail 11 which extends across near the top of the door in the form of a top rail 12 upon which the latch 13 of the present invention is mounted. As shown, the vault door is surrounded by a casing which includes a plate 14, the lower edge of which extends below the level of the door opening and constitutes in effect a flange with which the latch of the present invention co-acts.

The flange furnishes a shoulder or abutment against which the rim of the door will swing when the door is completely closed.

The latch of the present invention com-

prises a mounting block 15 which may be of the square formation shown, or any other desired formation, and the block rests upon and is secured to the top rail 12 preferably at a point near the free edge of the door. The mounting block serves as a mounting for a latch member 16, which, as shown, is of cylindrical formation and is slidably mounted within a cylindrical bore 17, although the latch member might be of square or other formation and mounted within a bore of corresponding shape.

The latch member is normally held in elevated position by the action of a coil spring 18 which occupies a position within the bore immediately beneath the latch member, and in order to prevent the latch member from being ejected upwardly from the bore by the tension of the spring, a pair of co-acting screw stops 19 and 20 are provided, the former of which is carried by the latch member and the latter by the block. The latch member is provided in its forward face with a groove 21 into which the stop 19 projects to furnish a closure for the lower end of the groove, while the stop 20 projects into the groove and thus limits the upward movement of the latch member after its upper end has been projected to a distance approximately equal to the depth of the shoulder furnished by the flange 14.

The latch member is provided in its end with a cross slot 22 of a depth and width to engage the flange 14, and the upper face of the latch member forwardly of the slot at the point 23 is flat while the rear upper face 24 is beveled, as indicated, and terminates in a knife edge 25, which is slightly lower than the edge of the face 22 on the forward side of the slot. The latch block is held in position by means of bolts 26, the heads of which are preferably countersunk within recesses 27 in the latch block. The bolts extend through the latch block and through the top rail 12 and are held by means of nuts 28 bearing against the lower face of the top rail.

In order to disable the latch member by holding its acting face below a position where it will engage with the flange 14, a pair of registering holes 29 and 30 are provided, respectively, in the latch member and the block, and by depressing the latch member until the holes are brought into register, and by inserting a disabling pin 31, the latch will be disabled or held out of com-

mission, which will permit the vault door to be completely closed for bolting or otherwise.

In order to provide against carelessness or inattention on the part of bank employees in opening the door in the morning, the pin 31 has attached thereto a chain or similar connection 32 the opposite end of which is connected to the plate 14 or other fixed portion of the casing, so that as the door is swung in opening, the chain connection or the like will be drawn taut, as in Fig. 4, and the pin automatically withdrawn from the registering holes 29 and 30 thereby releasing the latch member and conditioning it against an emergency.

Figure 5 shows a modification especially designed for heavy doors in which the latch is mounted on the inner edge of the casing 33 in position for the latch member 34 to engage with a recess 35 in the edge of the door, the door edge in this instance being beveled, so that the inner lip of the recess will stand higher than the outer lip to insure engagement against the latch member when the door is swung ajar. In this case the chain 32 will be connected to the door.

In use, the latch member will normally project above the top of the block, as indicated in the drawings, and if, in these circumstances, the vault door be swung closed, the beveled rear face 24 of the latch member will engage with the flange 14 or other flange-like projection and be depressed against the tension of the spring 18 until the knife edge 25 clears the rear edge of the flange, which will permit the latch member to spring upwardly into position to bring the slot 22 in position to engage and embrace the edge of the flange. The knife edge 25 being somewhat lower in position than the forward portion of the latch member, the latch member cannot thus be depressed sufficiently to prevent the forward portion of the latch member from engaging with the flange thus preventing a full closing of the door. When, however, it is desired to permit such full closing, the latch member can be thrust downwardly and held by the insertion of the disabling pin, which will then permit the latch device of the present invention to swing clear beneath the flange and permit the door to be closed to its fullest extent, which, in the construction indicated, will bring the edge of the door into abutment with the flange 14.

The length of the chain connection 32 may be made sufficient to permit a proper manipulation of the attached pin 31 from the outside of the door for disabling the latch prior to the closing of the door for the night. However, the chain will be so attached to the door casing that when the pin is drawn out and the chain falls back within the door casing, it will be concealed, or practically

so, against observation from without, and this fact, in conjunction with the fact that the latch itself is in a concealed position on the door, will make it impossible for intruders to detect the presence of the safety appliance of the present invention, which is important in that it prevents intruders from being forewarned which would otherwise enable them to disable the latch before imprisoning the bank employees within the vault.

With the door partly closed and latched, it will be impossible from without to either open or close the door, and, at the same time, a crack or crevice will be maintained around the door, so that anyone confined inside the vault will not be in danger of suffocation. The door may be easily opened from within by pressing down upon the exposed beveled surface 24 of the latch member with a tool or with the fingers, where conditions will permit, but an effort to press down and release the latch from the outside may easily be frustrated by thrusting the pin into the hole 30 which will prevent the latch member from being depressed sufficiently to clear the flange 14.

The device is one which is of extremely simple construction, and, at the same time, when proportioned and mounted with due regard to the range of movements required to ensure a proper functioning of the parts will constitute an efficient safeguard under the conditions of use for which the device is intended.

Although the construction of the latch has been described with particularity, and although the latch, as shown, is mounted upon the door, which is the preferred construction, rather than upon the casing, it is not the intention to limit the invention to a latch of the particular form shown, or mounted in the manner specified, since the means employed for automatically restoring the latch to effective operation by the opening of the vault door, are of more general application, so that it will be understood that the construction and arrangement may be varied without departing from the spirit of the invention.

I claim:

1. In a safety latch of the character described, in combination with a door and door casing, a latch secured to the door in proximity to the edge thereof and provided with a latch member adapted to co-act with a portion of the casing to hold the door ajar, disabling means adapted when inserted to hold the latch against operation, and a flexible connection between said disabling means and the door casing for withdrawing said disabling means upon the opening of the door to restore the latch to operative condition, substantially as described.

2. In a safety latch of the character de-

scribed, in combination with a door and door casing and a member projecting inwardly from the door casing, a latch block secured to the door in proximity to the edge thereof, 5 a latch member yieldably mounted within the latch block and having an acting face configured to engage with and be depressed by the projecting member and to re-engage therewith under tension to hold the door in 10 partially closed position, disabling means adapted when set to hold the latch member in depressed position, and means actuated by the opening of the door for retracting the disabling means to recondition the latch 15 for effective operation, substantially as described.

3. In a safety latch of the character described, in combination with a door and door casing and a member projecting inwardly from the door casing, a latch block secured to the door in proximity to the edge thereof, a latch member yieldably mounted within the latch block and having an acting face configured to engage with and be 20 depressed by the projecting member and to re-engage therewith under tension to hold the door in partially closed position, disabling means 25 in the form of a pin adapted to be inserted through the latch block and into the latch member to hold the latter in depressed position, and a connection between said disabling pin and the door casing for withdrawing the pin upon the opening of the door to restore the latch to effective operation, substantially as described.

abling means adapted when set to hold the latch member in depressed position, and a connection between said disabling means 30 and the door casing for retracting said disabling means upon the opening of the door to reposition the latch for effective operation, substantially as described.

4. In a safety latch of the character described, in combination with a door and door casing and a member projecting inwardly from the door casing, a latch block secured to the door in proximity to the edge thereof, a latch member yieldably mounted within 35 the latch block and having an acting face configured to engage with and be depressed by the projecting member and to re-engage therewith under tension to hold the door in partially closed position, disabling means 40 in the form of a pin adapted to be inserted through the latch block and into the latch member to hold the latter in depressed position, and a connection between said disabling pin and the door casing for withdrawing the pin upon the opening of the door to 45 restore the latch to effective operation, substantially as described.

HORTON J. COON.
